UNITED STATES PATENT OFFICE.

WILLIAM C. DEVEREAUX, OF DETROIT, MICHIGAN.

DOOR LATCH.

Application filed December 10, 1923. Serial No. 679,769.

This invention relates to latches and refers more particularly to those designed for use upon the doors of vehicle bodies.

An object of the invention is to provide a simple and reliable latch having a bolt that will enter its keeper even though the door upon which the latch mechanism is mounted sags when in open position and that will fit its keeper snugly to prevent the door from sagging when in closed position.

Another object is to provide a latch having a bolt that will remain in engagement with its keeper when the door is closed even though the vehicle body is subjected to torsional strains and stresses which increase the distance between the keeper and the outer edge of the door.

Another object is to provide a latch having simple and effective means for preventing the bolt from rattling when in engagement with its keeper.

Another object is to provide a latch having means for retaining the operating handle thereof in a pre-determined position with respect to the outer edge of the door when the bolt is in extended position.

With the above and other objects in view, the invention consists of certain novel features of construction, combination and arrangement of parts as will be more fully described and particularly pointed out in the appended claim.

In the accompanying drawing:

Figure 1 is a rear elevation of a door latch embodying my invention with the cover plate shown in dotted lines;

Figures 2, 3 and 4 are cross sections respectively on the lines 2-2, 3-3 and 4-4 of Figure 1;

Figure 5 is a horizontal cross section through a vehicle door showing my latch in plan.

Referring now to the drawing in which like characters of reference designate corresponding parts throughout the several views, the numeral 1 designates a case plate which is preferably secured to the inner side of a vehicle door 2 and which is provided at one edge with a laterally extending flange 3 that is secured to the outer edge of the door. Slidably mounted on the case plate is a bolt 4 having a relatively flat shank 5 extending between a pair of parallel struck-out ears 6 and having a relatively long enlarged head 7 extending through the flange 3 for engage-

ment with a keeper 8 upon an upright member 9 of the vehicle body.

In order that the door will be prevented from sagging when closed, I preferably provide the head 7 of the bolt with a substantially frusto-conical nose 10 that is adapted to fit snugly within a correspondingly shaped socket 11 in the keeper. Thus, should the door be sagging when it is moved to closed position the frusto-conical portion of the bolt head will engage the lower edge of the socket 11 and will automatically ride upwardly thereover and into the socket. This will cause the outer edge of the door to move from a sagging inclined position to the proper vertical position parallel to the upright member 9.

The bolt is normally retained in extended position by means of a helical spring 12 and the arrangement is preferably such that when the door is closed and the space between the flange 3 and the keeper is slight as usual, the bolt will be partially extended and that when the space between the flange and keeper increases while the door is closed due to torsional strains and stresses to which the vehicle body is often times subjected, the bolt will be extended further automatically by the spring 12 to remain in snug engagement with the keeper. Furthermore, as the nose of the bolt is adapted to fit the socket in the keeper snugly, the spring 12 will hold the bolt against rattling while in engagement with the keeper. One end of the spring 12 is rigidly secured between parallel lugs 13 struck out from the case plate, while the other end thereof abuts the forward end of a longitudinally extending slot 14 formed in the shank of the bolt.

For retracting the bolt, there is a curved lever 15 that is pivoted at one end to the case plate and that extends upwardly through the slot 14 and engages an upstanding lug 16 on the upper edge of the bolt. A cover plate 17 is arranged parallel to the case plate and is provided with forwardly projecting tongues 18 that extend through openings 19 in the lateral flange 3 and that are preferably riveted thereto. This cover plate is secured to the case plate by screws 20 that threadedly engage tubular spacers 21 which extend through the case plate and are riveted thereto. The cover plate is provided with an elongated open ended slot 23 that extends longitudinally

thereof and that registers with the bolt, the shank of the bolt being preferably cut away at its inner end so as to extend behind the cover plate. The lever 15 is limited in its forward movement by one of the spacers 21 and is preferably held in engagement therewith by means of a spring 25 that is coiled about another of the spacers 21. One end of the spring 25 abuts the lower lug 13 while the other end abuts the inner edge of the lever.

In order that the bolt may be retracted without moving the lever 15 by a person outside of the body, I preferably provide a rotatable hub 27 that is journaled in the case plate and that has an upstanding actuating arm 28 engageable with a curved arm 29 extending downwardly from the shank of the bolt. The hub 27 is also provided with a polygonal opening 30 that receives the operating shank 31 of a suitable handle 32 which preferably extends transversely of the shank. Thus, when the arm 28 is rocked by the handle 32 to retract the bolt, the lug 16 on the bolt will be disengaged from the lever 15 which will be held in engagement with the adjacent spacer 21 by the spring 25. When the lever 15 is used to retract the bolt, the arm 29 will be moved away from the actuating arm 28 so that the handle 32 will remain in normal position.

To dog the bolt, I have provided a cam member 33 that is adapted to be rotated by suitable key-operated mechanism 34 into engagement with an elongated recess 35 in the shank of the bolt. For this purpose the cam member 33 is preferably non-rotatably mounted on a hub 36 that is journaled in the plates 1 and 17 and that is provided with a polygonal opening 37 for engagement by the actuating shank 38 of the key-operated mechanism.

In the construction of vehicle bodies, it sometimes happens that there is quite a space provided between the keeper on the usual upright member and the outer edge of the door when the latter is in closed position. When such is the case only a very small portion of the ordinary bolt engages the keeper, consequently there is a possibility of an unauthorized person unlocking the door by disengaging the bolt from the keeper. With the present invention this is prevented for the reason that the bolt is

adapted to be extended by the spring 12 to 55 engage the socket in the keeper snugly even though the space between the keeper and flange 3 is greater than usual and the locking recess 35 is of sufficient length to receive the cam 33 in either partially or 60 fully extended positions of the bolt.

It is customary to have all of the outside operating handles of vehicle door locks or latches normally extend either horizontally or vertically with respect to the vehicle 65 body. With the present invention, the handle preferably extends horizontally when in normal position. To accomplish this the opening 30 is preferably arranged in the hub 27 so that one side of the shank 70 31, which is preferably square shape in cross section, will be normally disposed parallel to the flange 3. In order that the handle 32 will be returned automatically to normal position after being operated, I 75 preferably provide a coil spring 40 that surrounds the shank 31. One end of the spring 40 is preferably anchored in the usual escutcheon plate 41, while the other end thereof is anchored in a suitable washer 42 80 that is sleeved upon the shank 31 and that is secured in position thereon by lateral projections 43 on the shank.

In use, after the bolt has been unlocked by rotating the cam 33 out of the recess 35 the 85 door may be opened by rotating the handle 32 which is first moved against the tension of the spring 40 before it actuates the arm 28 to retract the bolt against the tension of the spring 12. The door may be opened from 90 the inside by simply operating the lever 15 to retract the bolt.

What I claim as my invention is:—

In a latch, the combination with a case plate, of a bolt having a shank slidably 95 mounted on said case plate, one longitudinal edge of said shank having an open longitudinally extending recess therein, bolt retracting means associated with said shank, and means for rendering said retracting 100 means inoperative including a shank rotatably mounted in said case plate upon one side of said shank and adjacent to the open recess therein, and a dog carried by the rotatable shank and adapted to swing into the recess 105 in said slideable shank.

In testimony whereof I affix my signature.

WILLIAM C. DEVEREAUX.
